CONVERTIBLE GUN TOY

John W. Ryan, Bel-Air, and Floyd Evan Schlau, Redondo Beach, Calif., assignors to Mattel, Inc., a corporation of California

Filed Feb. 2, 1966, Ser. No. 890

Term of patent 14 years

(Cl. D34—15)

Fig. 7

Fig. 6

Fig. 5

Fig. 10

Fig. 8

Fig. 9

Fig.11

Fig.12

FIG. 1 is a perspective view of a convertible gun toy, showing our new design;

FIG. 2 is a perspective view of the opposite side thereof;

FIG. 3 is a perspective view thereof when converted by placing the pistol type element having the telescopic sight in front of the pistol type element without the sight;

FIG. 4 is a perspective view of the opposite side of FIG. 3;

FIG. 5 is a side elevational view of the pistol type element with the sight alone when employed as a pop gun;

FIG. 6 is a top plan view of FIG. 5;

FIG. 7 is an end elevational view taken from the right of FIG. 5;

FIG. 8 is a side elevational view of the side opposite FIG. 5;

FIG. 9 is a bottom plan view of FIG. 5;

FIG. 10 is an end elevational view taken from the right of FIG. 8;

FIG. 11 is a perspective view thereof;

FIG. 12 is a perspective view of the opposite side of FIG. 11;

FIG. 13 is a side elevational view of the other pistol type element without the sight, the side opposite being identical;

FIG. 14 is a top plan view of FIG. 13;

FIG. 15 is a bottom plan view thereof;

FIG. 16 is an end elevational view taken from the right of FIG. 13; and

FIG. 17 is an end elevational view taken from the left of FIG. 13.

We claim:

The ornamental design for a convertible gun toy, as shown and described.
